UNITED STATES PATENT OFFICE.

HOWARD W. PARTLOW, OF UTICA, NEW YORK.

THERMOSTAT.

Original application filed January 25, 1924, Serial No. 688,555. Divided and this application filed October 6, 1924. Serial No. 741,922.

To all whom it may concern:

Be it known that I, HOWARD W. PARTLOW, a citizen of the United States, residing at Utica, in the county of Oneida and State of New York, have invented certain new and useful Improvements in Thermostats, of which the following is a specification.

This invention relates to improvements in thermostats, designed for use in connection with various heaters and mediums to be heated, as melting-pots and the like, and has for its object to provide a temperature regulator of the class, which is more sensitive and positive and more reliable than any other thermostat known to me. A further object is to provide a thermostatic element comprising two parts, one of said parts being hollow and inclosing the other part, the said hollow part preferably being constructed from ferrous metal having relatively low expansibility, as compared with non-ferrous metals commonly used for the purpose; the other part comprising a non-expansible member, and serving as a mechanical medium for transmitting the thermal actions of the hollow member to a train of compound levers and parts, by which fuel governing and dispensing valves, or other mechanisms may be operated or controlled. And a further object is to generally improve, simplify and render more accurate and reliable thermostatic devices of the class, especially applicable for controlling burners that are supplied with gas at higher than commercial pressures.

I attain these objects by the means set forth in the detailed description which follows, and as illustrated by the accompanying drawing, in which—

Figure 1 is a central vertical section, showing a gas-governor to which my thermostat is operatively applied; also showing the thermostat submerged in the contents of a melting-pot. Fig. 2 is a transverse vertical section, taken on line 2—2 of Fig. 4. Fig. 3 is an elevational view of the perforated member and certain of the compound levers operated thereby. Fig. 4 is a top-end view of the thermostatic part and Fig. 5 is a horizontal section, taken on line 5—5 of Fig. 1.

In the drawing, 2 represents the hollow body of a gas-governor, such for example, as is employed in connection with melting-pots, as A, water-heaters, and the like, and which is adapted to be charged with combustible

gas, or other fluid pressure, by which the supply of gas to the burner, A', may be controlled. The gas or fluid pressure enters the body through a pipe 2', and discharges through a pipe 2". The outflow of the fluid pressure from the governor is controlled by a spherical valve 3 which is disposed in a tubular part 4, the latter being disposed in line and communicating with the pipe 2". 60 4' represents the seat of the valve. The part 4 is adjustable for varying the position of the seat 4' relatively to the valve 3 (see Fig. 1), by means of a screw 5, the head 5' of the screw being disposed outside of the body, and being supported by the cover 2^b. The screw 5 is manipulated by means of a disc 6, by which the adjustment of the valve seat is regulated. The disc supports a dial 7, by which the temperature of some medium, as α , may be predetermined. The valve 3 is suspended from one end of a relatively long lever 8, the opposite end of said lever being supported by a pair of dogs 9 and 10, which respectively engage fulcrum pins 8' and 8", as shown in Fig. 1. The dogs 9 and 10 are pivoted to a block 12, by screws 9^a, and are provided with similar depending ball-portion 9^c—10^c, which normally engage the top face of an arm 13' of a vertically disposed oscillate lever 13, the said lever being formed with a perforated lug 13^a, which is pivoted to the block 12, by a screw 13^b. The lateral swinging of the lever 13, as indicated by the dotted lines in Fig. 1, effects the spreading of the top-ends of the dogs 9—10, and tilts the forward end of lever 8 in the direction for lifting the valve 3 away from its seat (see dotted lines in Fig. 1). This allows the fluid pressure contained in the body 2 to escape through the pipe 2", for supplying fuel to the burner A', or for performing other work.

14 represents an elongated hollow metal leg or part, which depends from the body 2, to which it is detachably secured by means of a flange 14', and screws 14^a. The bottom of the body has an opening 2^c, which registers with the chamber of the leg 14. The lever 13 extends downwardly in the leg, and is oscillated by a similar but inverted lever 15, which is pivoted eccentrically near the lower end of the leg by a screw 15'. The levers 13—15 are preferably disposed in the same plane vertically, and their free ends overlap and are held in frictional engagement, and also in alinement by a fork

15^a. The lever 15 is provided with a horizontal arm 15^b, by which said lever and lever 13 are rocked laterally, as shown in Fig. 1. A spring 8^c tends to normally depress the lever 8 to the full line position shown in Fig. 1, for allowing the closing of the valve 3 by gravity.

The valve 3 and the several dogs and levers are operated, as a train, by a thermostatic element, or device, which consists of a tube 16, the latter depending axially from the leg 14, and the top end being threaded to the lower end of the leg. The lower end 16^a of the tube is internally and externally threaded and is closed and sealed by a screw-cap 17. The tube 16 is preferably made of steel, and has a relatively low expansibility, as compared with brass and other metals commonly employed for thermostats of the class. Within the tube 16 is disposed a rod 18, which may be made of steel or other material preferably having less expansibility than said tube. The object of this particular construction is to restrict the thermal actions of the governing device entirely to the tube 16, instead of to a combination of parts, as heretofore. By providing a single thermostatic element, as 16, of relatively low expansibility, I am able to positively and accurately control the gas valve 3, or other mechanism, without the usual interferences and uncertain and uncontrollable actions of any of the related parts, and by rigidly connecting the neutral rod 18 to the remote end of the tube, ensures adequate linear movement, as well as power, for positively operating the train of compounding levers and parts that effect the seating and unseating of the valve 3. The lower end of the rod 18 is threaded and is made rigid in the corresponding end of the tube 16, by a nut 19, which is first screwed onto the rod until it engages an adjacent shoulder of the tube, after which a locking nut 20 is screwed into the tube and against the nut 19. The top end of rod 18 is forked, and straddles and is pivoted to the arm 15^b of lever 15, by a screw 15^c. By this arrangement, the slightest contraction or expansion 50 of the tube 16, rocks the levers 13—15, dogs 9, 10, and lever 8, in a positive manner, as shown by the full and dotted lines in Fig. 1.

By employing ferrous metal of comparatively low expansibility, the temperature changes of the melting-pot A rarely effects the expansion or contraction of the thermostat 16 more than a few thousandths of an inch. But owing to the fact that the rod 18 is made fast to the extreme lower end of the tube 16, whatever thermal action takes place is communicated by the rod to the train of compounding parts, and effects the positive raising and lowering of the valve 3, and by reason of the peculiar construction and arrangement of the thermostat and rod 18,

the same positive operation of the valve takes place whether or not the tube 16 is fully or only partially submerged in the medium x. The lower end of the thermostat being free from contact with the bottom or sides of the melting pot, the lengthening and shortening of the said tube, although it is rigid to the leg 14, cannot affect the slightest shifting of the levers that control the valve, except through the medium of the neutral rod 18, as explained. 70 75

In order to obviate any tendency of the leg 14 to contract or expand when the thermostat is deeply submerged and therefore disturb the valve 3, the levers 15 and 13 are overlapped and are free to move endwise relatively to each other without exerting any operative effect upon the dogs 9—10. In the present showing the expansion linearly of the tube 16, effects the movement of the several levers, as from the full line to the dotted line position shown in Fig. 1, for opening the valve 3; while the contraction of the tube effects the reversal of the lever 15, and allows the other parts of the train 90 to become reversed by the gravitation of the valve 3. 80 85

This case is filed as a division of my pending application, Serial No. 688,555, filed Jan. 25, 1924, for thermostat. 95

Having thus described my invention, what I claim, is—

1. The combination with a gas governor including a valve for dispensing the gas, a lever and a pair of dogs for controlling said dispensing valve, of a metal tube of low expansibility supported by the governor, a rod disposed axially in the tube, the lower end of said rod being anchored near the lower end of the tube, its top end being free from the tube, and a pair of levers interposed between said rod and said dogs adapted to be rocked laterally by the endwise movement of said rod for effecting the operation of said dogs and said valve. 100 105 110

2. The combination with a gas governor including a valve, a lever and a pair of dogs for controlling the valve, of a metal tube of relatively low expansibility supported by the governor, a rod of lower expansibility than said tube disposed axially in said tube, said rod being anchored near the bottom end of said tube and movable endwise by the expansion and contraction of said tube, a pair of levers interposed between the rod and said dogs, one of said levers being frictionally engaged with said dogs, the other lever being connected to said rod, said lever adapted to be rocked laterally by the endwise movement of said rod for effecting the operation of said valve, and means for preventing the operation of said pair of levers by any thermal action except that which is transmitted by said rod. 115 120 125

3. The combination with a hollow body 130

adapted to be filled with gas, including a valve for dispensing the gas, of a thermostatic element comprising a tube of relatively low expansibility adapted to be submerged in a medium that is being heated, a burner for heating the medium supplied with fuel by the valve, a rod substantially neutral to expansion and contraction enclosed by said tube and rigidly connected to the free end of the tube, and a pair of overlapping frictionally engaged levers, one of said levers being operatively connected to said rod, and means actuated by the other lever for effecting the opening of the dispensing valve and the closing of the auxiliary valve.

4. The combination with a melting-pot, and a burner for heating the pot, of a governor comprising a hollow body adapted to be charged with fuel gas, a valve in said body, a lever for operating the body valve, a pair of dogs supporting and operating the said lever, a thermostat adapted to be submerged in the medium heated in said pot comprising a tube of low expansibility, a rod disposed in said tube, the lower end of said rod being anchored in the bottom of the tube, a hollow leg depending from said body and supporting said tube, eccentrically pivoted levers disposed vertically in said

leg, one of said levers connected to and rocked by said rod, the corresponding ends of said levers being overlapped and the uppermost lever adapted to be moved laterally by the lowermost lever, and the remote end of the uppermost lever engaging and rocking said dogs.

5. A thermostatic control for heaters comprising a gravitational valve, a lever for raising said valve, a pair of dogs for supporting and tilting said lever in the direction for opening said valve, a pair of levers for actuating said dogs, said levers being disposed in the same plane and the adjacent ends thereof being overlapped, the remote ends of said levers being pivoted, a tube adapted to be submerged in a medium to be heated, and a rod disposed in said tube, the lower end of said rod being anchored in the bottom of the tube, the upper end thereof being pivoted to the lowermost lever of said pair adapted to rock the overlapped ends of said levers laterally by the expansion of said tube for lifting the said valve, said valve adapted to close by gravity and to reverse the movements of all of said operating parts except the lowermost lever of said pair by the contraction of said tube.

In testimony whereof I affix my signature.
HOWARD W. PARTLOW.
